UNITED STATES PATENT OFFICE.

ALFRED W. GIBBS, OF ALTOONA, PENNSYLVANIA.

ROD-PACKING DEVICE.

SPECIFICATION forming part of Letters Patent No. 621,063, dated March 14, 1899.

Application filed June 1, 1898. Serial No. 682,239. (No model.)

To all whom it may concern:

Be it known that I, ALFRED W. GIBBS, a citizen of the United States of America, residing in the city of Altoona, in the county of Blair, 5 in the State of Pennsylvania, have invented a certain new and useful Improvement in Rod-Packings Devices, of which the following is a true and exact description, reference being had to the accompanying drawings, which 10 form a part thereof.

While my invention in some of its new and useful features relates to rod-packings and stuffing-boxes in general, it more particularly relates to that class of them wherein a reciprocating rod is surrounded and ridden with a certain freedom of motion by a built-up 15 holder for packing; and in its preferred form, by which it is hereinafter illustratively described, my said invention has a special relation to that further class of rod-packing devices wherein the rod, formed with an enlarged 20 end or ends, requires, for the purposes of assembling and stripping, those parts of the device which meet upon it to be divided and 25 separable.

The chief object of my invention is to provide an improved stuffing-box, one which shall not leak by reason of structural defects, and to this end to provide an improved mechanism or holder for the packing (preferably 30 metallic) which meeting about rides the rod with tight and wear-compensating joints.

Further objects are to provide improved devices for lubricating the rod or reciprocating member with which such devices are associated in use, and in doing so to provide a definite outlet or passage of least resistance from such point within the steam-confining or equivalent fluid-under-pressure-confining 35 elements of the combination as shall prevent the dislocation or blowing out of an outlying fibrous lubricant-distributer, such as I prefer to employ in my invention in its entirety; also, to provide an improved device for retaining 40 a lubricant-distributer or swab; also, to prevent creeping and loss of lubricant when fluid and by reason of the capillarity of close-jointed surfaces, together with such other objects as will be apparent from this specification 45 as a whole.

The new and useful features of my invention will be found segregated in the conclud-

ing claims, and reference now being had to the accompanying drawings, which form part of this specification, they will be found 55 to illustrate my invention as follows:

Figure 1 is a partially-sectional side elevation of a portion of the cylinder-head, stuffing-box, rod, and guide mechanism of a steam locomotive-engine embodying my invention 60 in the preferred form, the rod and built-up parts thereof being shown unsectioned. The plane of sectioned parts is vertical and passed through the box's long axis. Fig. 2 is an enlarged sectional side view of the built-up 65 parts of said device, the rod fragment which is packed being shown unsectioned, the plane of the section also as in Fig. 1. Fig. 3 is a central cross-section through the lubricating device, with surrounding case or gland-breeching shown in elevation. Fig. 4 is a cross-section, upon line $y-y$ of Fig. 2, of details; and Fig. 5 is an end view of a preferred composite packing-follower.

In detail (see Fig. 1) O indicates the usual 75 flanged projection of a locomotive-cylinder's rod emerging end, and o the cavity or gland-socket therein.

E denotes the rod to be packed, and has upon its outer end a slotted conical enlargement E' , by which enlargement the rod is removably engaged with a corresponding conical socket x in cross-head X. This socket is bored blind, save for a driftway x' . Into this driftway an integral drive-stub e' of the rod-head E' projects and waits use in stripping the parts E' and X from each other.

Into the muzzle of the cavity o (which cavity communicates to the cylinder's bore by a passage o' of sufficient diameter to admit the 90 rod end which has to pass through it) there is inserted the tubular follower part h of the breeching or flanged packing-case H. This case is held to place by nuts t and stud-bolts t' , which, passing through its face, are fixed 95 in the usual way in the stuffing-box O. Between the flange h' of case H and the box-face o' an annular gasket g , being clamped, forms a tight joint. The bore of case H is of irregular shape, but at all parts of its 100 length of sufficient diameter for free passage of the enlarged rod-head E' aforesaid. The muzzle end or outer bore of the case H has a cylindrical cavity h^2 and forms a seat for

a swab-cup R, which cup, being a split ring internally chambered, has a U-shaped section. (See Figs. 2 and 3.) It is also perforated through its back with ports r and, being filled 5 with a fibrous swab W, serves to distribute upon the face of the rod E, which it surrounds, substantially all such lubricant as may be fed to it by way of the oil-hole h³, for parts w of the fibrous swab projecting into the ports r 10 act to wipe off and "return to the fold" such portion of the said lubricant as, being fluid by reason of capillary action, tends to waste by creeping into the joints formed by the meeting faces of said swab-ring and its seat, 15 the point of absorption being on the lines where said joints open and girdle the rod and the outlet to waste between the comparatively crude joints of a solid swab-retaining ring s (bolted to the face of the case H) and 20 said case's face—viz., the joint s'. Now such capillary creeping those portions of the swab which project or reach into the back of the swab-ring seat through the ports r prevent, and by superior affinity win back and apply 25 to the rod lubricant otherwise going to waste, for which reason said swab and ported ring become a most economical distributor of lubricant.

An inwardly-projecting flange h⁴ forms the 30 bottom of the swab-ring socket. The inner face h⁵ of this flange is preferably formed oblique and vanishes at its root into a cylindrical chamber h⁶. This chamber h⁶ extends thence a short distance and in turn vanishes 35 into a "hollow" spherical seat H', forming one member of what in packing devices of preferred sort is denominated the "ball-joint." Into this socket the ball-head g' of a ball-ring G fits with a tight but swiveling joint. The 40 back face g² of ball-ring G is faced square to fit with tight joint corresponding front face a' of a continuous cup or packing-holder part A. This joint is to allow the riding parts to move transverse to the line of the rod and, 45 combined with the swiveling freedom given by the ball-joint aforesaid, to permit them to follow the most complicated rod movements, yet all, if the component parts be held properly to place, without loss of steam.

50 The cup part A of the packing-holder I provide with a central thoroughfare a for the passage of the enlarged rod end E', and concentric therewith taper-bore it, the larger end of the cavity a² thus formed being placed toward the working fluid. Into the cavity a² I place a snug-fitting split tubular cone-liner B B', the bore of which, where of least diameter, exceeds that of the rod E, so that when 55 in place within the holder or cup ring A the split meeting faces b b' come together with a joint the degree of tightness of which when in use is to large extent due to the wedge action of the cup A, said action being then excited by endlong forcing of the parts B B' 60 down the declivity of the hollow cone a under the combined forcing of the fluid under pressure and a spring-actuated follower, herein-

after described. Dowels d, fixed in one part, as B, and dowel socket-holes d², bored to register in the other, serve to align the parts B B' 70 in assembling. Moreover, as their meeting faces b b' are formed true and disposed in radial plane it is obvious that a high degree of compression can be brought to bear on them by "driving up" the split parts B B' 75 into the cavity a². But leaving this incipient recitation of the functional value of my improved packing-holder parts and returning to descriptive detail of the drawings, it will, on again referring to Fig. 2, be seen that the 80 split and separable packing-holder parts B B' upon their outer end b² come near to and girdle the rod E. They, however, preferably not quite contact with it. Internally I fashion said parts into a feature common in packing-holders—namely, abrupt and low inclined merging cone-cavities b³ b⁴. These cavities are bored out concentric to the line of the rod and have stacked in them a pile of preferably 85 segmental and metallic packing-blocks P. 90 These blocks, like all other parts that meet close around the rod which has the enlarged head or heads, are of course split and when released from the holder A B B' separable from each other and the rod. To hold this assemblage of blocks or packing proper to place, (which is a snug steam, &c., tight fit about the rod and a similar one in their nest in the composite holder A B B',) I employ a composite follower actuated by a spring. To be 95 well behind the packing-blocks P this follower has to come close to the rod, and as the rod has an enlarged head E' it has also to be composite. I therefore fashion the cylinder not as is usual for such devices—namely, with 100 cylindrical threaded screw-engaging parts—but as follows: of a split follower K K', having an abutment-flange k and a cylindrical tubular extension k', the whole meeting with small clearance about the rod, and of a continuous keeper or retaining-ring L, which being bored to fit slidingly onto the said extension k' when so slipped on keeps the split separable parts of the former in place and together. The aperture of the ring L is of 105 course sufficient for the passage of rod-head E'. As a device for forcing the follower toward the packing P, as well as thrusting all 110 the joints of the rod-riding and built-up internal structure of the gland into close association, a spiral spring S abuts, one end against the back of said retaining-ring R and (with its coils compressed) the other end against the shoulder o², where the gland-socket proper ends. Should some steam leak past 115 any of the joints of this built-up packing, and whether such leak be for the lack or in spite of my above-described improvement in packing-holder devices, I furnish a duct v, leading from the chamber h², above alluded to, and, 120 extending it through the walls of the case H, give a ready escape to the atmosphere for such steam or other fluid under pressure as 125 has forced the passage of the joints or come 130

by way of scores cut in the rod or packing P. For were it not for the less resistance of the vent v there would be, as heretofore has been the custom, a flow-out through and to the detriment of the swab. As such flow-out often resulted not only in waste of oil and swab-packing, but even in the destruction of the swab-retaining devices, the value of this branch of my invention is too obvious and material to require further enlargement.

The foregoing description of parts has, as an indispensable incident, involved a statement of their several operations. Taken together their operation is obviously to ride the rod, lubricate it, pack it most efficiently, provide against loss of lubricant, offer a passage of least resistance to such steam as does force the main defences, and in general facilitate both assembling and stripping acts. It may, however, be pointed out with propriety that the act of stripping the liner parts B B' from their cup A is readily accomplished by tapping the outer ends of said parts B B' where they appear in the rod-thoroughfare a of the cup A. A blow or two should, if they stick in the cone-cavity, readily start them. Withdrawn from the cavity a^2 they naturally separate from the rod.

By the above-illustrated case, which is the usual one of a rod of circular cross-section, I do not intend to limit myself to a rod of circular section only, for my device in the particular of cross-sectional form of rod is obviously as various as other rod-packing devices.

Having now described my invention, what I claim as new, and desire to secure by Letters Patent, is—

1. The combination with a stuffing-box member, as case H, said member having a chamber, as h^2 , of a U-shaped swab-ring, said ring having a ported back, and a fibrous swab, substantially as described.

2. The combination with a stuffing-box member, as case H, said member having a chamber, as h^2 , of a U-shaped swab-ring, said ring having a perforated back, a fibrous or equivalent bulbous swab, and a retaining-ring, as s, adapted to hold said swab-ring, substantially as described.

3. The combination with a work-rod and the stuffing-box cavity thereof, of a rod-riding packing-holder, said holder being built up of a continuous hollow female wedge part A and of a split male wedge part B B', said latter composite part being formed with a conical bore, the least diameter of which exceeds that of the rod as and for the purposes specified.

4. The combination with rod E having enlarged head, as E', of the continuous packing-holding cup A apertured for the passage of said rod-head and provided with conical cavity a^2 , the split male liner parts B B' having jointed meeting faces b b' , and a packing-cavity, as b^3 b^4 , packing, as P, adapted to coat therewith, an abutment, as ball-ring G, for the cup A, and a follower operating to force the packing P into said cavity of the liner parts B B', substantially as described.

ALFRED W. GIBBS.
